COVER

Daniel K. Copell, New York, N. Y.

Application December 29, 1939, Serial No. 311,469

3 Claims. (Cl. 206—41)

This invention relates to a structurally and functionally improved cover or casing, primarily intended for use in connection with smoking pipes.

It is a well appreciated fact that any number of covers or tobacco pouches have heretofore been marketed, and which have provided a receptacle for a pipe. These have offered, among others, the disadvantage of being cumbersome and expensive, aside from the fact that they have been difficult to apply, and when the pipe has been housed therein, they have substantially excluded any possibility of ventilation.

Thus, it is an object of the present invention to provide a cover or casing for use in connection with a pipe, and which casing will be compact and of simple construction and capable of being produced at a nominal figure.

A further object is that of providing a cover which may quickly be applied to or removed from the pipe and which, when in applied position, will effectively guard against any staining or burning of the pocket in which the pipe may be placed by the user.

A still further object is that of furnishing a device of this type and which, with the aforementioned advantages, will still permit of the pipe being subject to ventilation.

Another object is that of designing a cover which will embody a construction such that it may be largely produced by automatic machine methods and which—within limits—will effectively house pipes of various sizes.

With these and other objects in mind, reference is had to the attached sheet of drawings, illustrating one practical embodiment of the invention, and in which:

Fig. 1 is a perspective view of the cover in closed position;

Fig. 2 shows the same in use and as initially applied to a pipe;

Fig. 3 is a fragmentary plan view of the pipe as shown in Fig. 2 and illustrating the cover in partially applied position, and

Fig. 4 is a view similar to Fig. 2, but illustrating the cover completely applied.

In these figures, the numeral 10 indicates the complete assembly which includes a pair of side walls 11 and 12, secured together as, for example, by stitching. The configuration of these side walls may be such, and the stitching may be interrupted, to provide an opening defined by a neck portion 13 of a diameter such that it may encircle the stem of a pipe.

As shown, the stitching is also interrupted ad-

jacent the top edges of the side walls and these edges may be secured together by suitable fastening means. While the latter may take different forms, it is preferred, according to the present invention that a slide fastener assembly be provided at this point, and including fastening elements 14, and a slide or actuator 15.

With a unit of this character, it is apparent that a container of a "semi-covering" type is furnished. Employing a pipe including a stem 16 and bowl 17, the former may simply be threaded through the cover and passed out through the neck portion 13 thereof. No effort or thought will be required in making this application, which has been illustrated in Fig. 2.

Thereafter, by simply grasping the actuator 15 and pulling the same upwardly and rearwardly, the entire cover is caused to rotate around the bowl of the pipe so that first the parts of the cover snugly embrace the bowl and those portions of the stem adjacent the same, and secondly the actuator traverses elements 14 to secure a closing of the cover. In this connection, it will be appreciated that due to the more or less conventional pipe configurations, the movement of the cover, with respect to the pipe bowl, will cause what might be termed a camming or wedging action of the parts of the cover to occur with respect to the pipe. This will cause the neck portion to be drawn snugly into contact with the stem and such action may be emphasized if the neck portion embodies a greater or lesser amount of resiliency.

In removing the cover, it is apparent that by simply reversing the pull on the actuator 15, the cover will be caused to rotate in a reverse direction with respect to the pipe bowl, and may, thereupon, be readily stripped from the pipe by shifting the entire cover rearwardly along the stem.

In any event, with the cover in position, the bowl of the pipe will be effectively protected and any contents of the same will be prevented from coming in contact with adjacent surfaces. At the same time, the stem will be exposed to the atmosphere, and air may accordingly flow over and past the same.

It will also be understood that with the cover in position the pipe may still be used without danger of ashes being blown out of the pipe bowl. In other words, the cover functions as a windshield, and sufficient air may be drawn through the closure to permit of an adequate flow of air through the bowl and the bit of the pipe. On the other hand, if with the cover in

position the pipe is placed in the pocket, it is found that the "smothering" effect of the cover is such that the fire in the bowl is quickly extinguished. As is also obvious, the cover may be applied to pipes of virtually any desired length in that with the configuration as illustrated, the bit and stem may be inserted through the main opening of the cover and out through the secondary opening and substantially regardless of the over-all length of the pipe.

Thus, among others, the several objects of the invention, as specifically aforementioned, are achieved. Obviously, numerous changes in construction and rearrangement of the parts might be resorted to without departing from the spirit of the invention, as defined by the claims.

Having described my invention, what I now claim is:

1. A cover for a pipe and including a receptacle presenting side walls to be disposed adjacent the side faces of a pipe bowl, said side walls presenting a pair of separate openings in their meeting edges, one of said openings being relatively restricted and to permit passage merely of the stem of a pipe, and the second of said openings being relatively large and permitting of the passage therethrough of the pipe stem and bowl, said stem being extendable through and beyond said relatively restricted opening to be freely exposed to the atmosphere beyond said receptacle, fastening means to retain against separation the edges of said second opening and including an element shiftable in the direction of the end of the pipe stem to render "said fastening means

operative and whereby to rotate said cover into snug contact with the bowl of said pipe and a neck portion forming a part of said cover and defining the first named opening therein to provide a sheath of constricted diameter and limited length to encircle those portions of the pipe stem adjacent the bowl thereof.

5 2. A cover for the bowl and adjacent portions of a pipe, said cover including a hollow body 10 presenting an edge portion interrupted to provide a pair of separate openings, the first of said openings being permanently unobstructed and adapted to afford passage for the stem of a pipe inserted through the second opening and closure 15 means associated with the second opening and extending to a point short of the said first opening.

3. A cover for the bowl and adjacent portions of a pipe, said cover including a hollow body 20 presenting an edge portion interrupted to provide a pair of separate openings, the first of said openings being permanently unobstructed and adapted to afford passage for the stem of a pipe inserted through the second opening and closure 25 means comprising two series of cooperating elements, one secured adjacent each of the opposite edges of said second opening, and an operating member mounted to traverse said elements to effect locking cooperation thereof as said member moves over the same in a direction towards 30 said first opening, said operating member occupying a position short of said first opening with said second opening closed by said elements.

DANIEL K. COPELL.
